UNITED STATES PATENT OFFICE.

HERMAN HENRY BOKELMANN, OF NEWARK, NEW JERSEY, ASSIGNOR OF
ONE-HALF TO HENRY PURCELL, OF SAME PLACE.

FRUIT OR OTHER JAR.

SPECIFICATION forming part of Letters Patent No. 603,020, dated April 26, 1898.

Application filed May 26, 1897. Serial No. 638,316. (No model.)

To all whom it may concern:

Be it known that I, HERMAN HENRY BOKELMANN, a citizen of the United States, residing at Newark, in the county of Essex and State of New Jersey, have invented certain new and useful Improvements in Fruit or other Jars, of which the following is a specification.

My invention relates to improvements in fruit or other jars used in preserving food products.

It frequently happens in the fruit-jars in common use that the cover, by reason of the sugar or sticky substance in the contents of the jar, becomes so firmly attached to the jar as to be difficult of removal without breaking the jar or cover. Besides this, as no provision is made in these jars for the escape of air when the cover is put on, fermentation may result and spoil or injure the contents. Such fermentation is not likely to be noticed until the cover is removed or, as often happens, until the goods have been sold, at which time, by reason of the spoiled goods, the dealer's reputation is liable to be injured. Again, nearly all the jars in use require clamping or screw devices to hold the covers on, and these devices are often expensive and complicated in operation. My device is intended to obviate all these difficulties.

In the accompanying drawings, forming part of this specification, like letters of reference designate like parts.

Figure 1 illustrates a cross-section of a fruit-jar and cover. Fig. 2 illustrates a plan view of the under side of a fruit-jar cover.

In Fig. 1, A indicates the top of a fruit-jar in cross-section.

B indicates the cover of a fruit-jar in cross-section.

C shows a plug, preferably of wood and of the shape shown.

D D indicate corrugations on the under side of the cover B.

E E indicate lugs on the inside of the cover B, adapted to engage a groove in the outside of the jar.

F shows a hole preferably in the center of the top of the cover B to admit the plug C.

G G indicate a groove at right angles near the top of the jar and outside it, encircling

the jar. This groove contains a filling substance X, preferably flat and of rubber, encircling the jar. In this groove and over the filling substance X the lugs E E of the cover B fit loosely when the cover is placed on the empty jar. These lugs E E are in the form of an annular ring extending all the way around on the inside of the cover B, as shown in Fig. 2.

60 H is a shoulder encircling the jar.

In Fig. 2 the corrugations D D D D are shown, the intersecting channels between them, and the lugs E E.

In operation I fill the jar with the goods to be preserved nearly level with the top and put on the cover, pressing it down until the lugs E E enter the groove G and bear upon the rubber band X. In this operation the corrugations D D D D cause some of the contents to escape in the direction indicated by the arrows through the hole F and force out all or nearly all of the air. I then drive the plug C into the hole F, using some force, so that it may be retained. The moisture of the contents will swell the plug C and hold it firmly in place. I have now excluded all or nearly all of the air from the jar. After standing the contents tend to settle, which, as no air can enter from outside the jar, produces a partial vacuum between the top of the contents and the under side of the cover. Atmospheric pressure will now force the cover down, the lugs E E bearing on the rubber band and sliding in the groove G G, and as long as the partial vacuum exists inside the jar the cover will be firmly held thereon. As there is little, if any, air within the jar, fermentation of the contents is not likely to result. Should the goods, however, ferment, the gases of fermentation will exert a back pressure on the cover, which becomes greater as fermentation proceeds, and this back pressure will finally force the cover from the jar, thereby indicating in an unmistakable manner that the contents have spoiled and preventing accidental sale of damaged goods.

90 95 99 What I claim is--

1. As a new article of manufacture a fruit or other jar and cover, said cover having a hole near its center, a plug fitting said hole, channel-cut corrugations on the under side

of said cover and lugs, said jar being encircled near its top by a groove and shoulder, said groove containing a filling substance and adapted to admit and hold said lugs, substantially as described.

2. In a fruit or other jar a cover having a hole near its center, a plug fitting said hole, channel-cut corrugations on its under side and lugs, in combination with a jar, said jar encircled near its top by a groove and shoul-

der, said groove containing a filling substance and adapted to admit and hold said lugs, substantially as described.

In testimony whereof I have hereunto set my hand, this 17th day of May, 1897, in the presence of witnesses.

HERMAN HENRY BOKELMANN.

Witnesses:

LOUIS MATHOX,
C. TIEDEMANN.
